BRAKE MECHANISM

William J. Andres and Frederick E. Strohm,
Pittsburgh, Pa., assignors to Bendix-Westing-
house Automotive Air Brake Company, Pitts-
burgh, Pa., a corporation of Delaware

Application October 6, 1939, Serial No. 298,324

12 Claims. (Cl. 303—54)

This invention relates to fluid pressure control mechanism and more particularly to a valve device for controlling fluid pressure systems.

One of the objects of the present invention is to provide a novel fluid pressure control valve mechanism of the self-lapping type wherein a simplified construction is achieved by combining a portion of the valve assembly with the manually-operable member.

Another object is to provide, in a device of the foregoing type, a combined pedal and valve mechanism wherein the valve-graduating spring is mounted on and carried by the pedal, this arrangement facilitating assembly of the apparatus as well as inspection and repair procedures.

Still another object is to provide a novel control valve mechanism constituted in such a manner as to materially decrease valve vibration and chatter during operation thereof.

A further object comprehends a novel and compact arrangement of parts in a mechanism of the foregoing type, which will be unusually efficient in operation and capable of economical manufacture.

Other objects and novel features of the invention will appear more fully hereinafter from the following detailed description when taken in connection with the accompanying drawing illustrative of one form of the invention. It is to be expressly understood, however, that the drawing is utilized for purposes of illustration only and is not designed as a definition of the limits of the invention, reference being had for this purpose to the appended claims.

In the drawing, wherein similar reference characters refer to like parts throughout the several views:

Fig. 1 is an axial sectional view of a control valve mechanism constructed in accordance with the principles of the present invention, and

Fig. 2 is a sectional view taken along lines 2—2 of Fig. 1.

Referring more particularly to Fig. 1, the invention is disclosed therein as embodying a self-lapping valvular mechanism including a casing 3 formed of upper and lower sections 4 and 5 respectively. The casing may be secured to a support, such as the floorboards of the vehicle, in any suitable manner so as to be readily accessible to the vehicle operator. As shown, the casing is divided into a plurality of chambers, a partition 6 being provided and forming in said casing an outlet chamber 7 and an exhaust chamber 8, the latter being connected to the atmosphere through an opening 9. The lower casing section 5 is so

formed as to receive an inlet housing member 10 forming with said casing section 5 an intake chamber 11, an intake valve seat member 12 being securely maintained in the position shown by the housing member 10.

Valve means are provided for controlling the flow of fluid pressure from the intake chamber 11 to the outlet chamber 7 and from the latter to the exhaust chamber 8, and, in accordance with the present invention, such valve mechanism is so constituted as to be self-aligning and to allow substantially unimpeded flow of fluid past the intake valve portion thereof. As illustrated, such means are constituted by exhaust and intake valves 13 and 14 respectively, said valves being of spherical form and rigidly interconnected as by means of a rod 15. A single spring 16 seated upon the intake valve seat member 12 is employed as the sole support for the valves 13 and 14, and, as shown, such spring normally tends to urge the valves upwardly in order to effect a closure of the intake valve. It will be perceived that, with the valve constructed as above described, an exceedingly simple structure is provided and one wherein in tight closure of the intake valve will be insured irrespective of lateral misalignment of the valve. The construction, moreover, avoids the use of complicated guide structures for the intake valve which would otherwise impede the flow of fluid pressure to the outlet chamber.

In order to actuate the valves 13 and 14 for purposes of controlling the flow of fluid pressure to the outlet chamber and also in order to control the communication between the outlet chamber and the exhaust chamber, a valve-actuating plunger 17 is utilized which is provided with an axial bore 18 forming an exhaust passage. This plunger is threadedly received by the lower end of a tubular member 19 which serves to lock the plunger in the position shown, and which is provided with exhaust openings 19a.

Secured to the valve plunger 17 is a pressure-responsive element constituted by a diaphragm 20, clamped between the two casing portions 4 and 5 and separating the exhaust chamber 8 from the partition 6. This diaphragm is securely maintained in position upon the plunger 17 as by being interposed between an annular shoulder 21 formed on the plunger and a plate 22, the latter being maintained in firm engagement with the diaphragm as by means of a collar 23 threadedly received by the upper portion of the plunger 17.

Novel means are provided by the present invention for effecting operation of the valve mech-

anism heretofore described, and, as shown, such means include a precompressed graduating spring assembly 24 positioned exteriorly of the casing 3 and operatively associated with a manually-operable pedal member 25. More particularly, the pedal member 25 is pivotally mounted on the upper casing section 4 as by means of a pair of ears depending from the rear portion of the pedal member, one of said ears being indicated at 26. The ears carried by the pedal member cooperate with ears 27 formed on or secured to the casing section 4, a rod or pin 28 serving to interconnect the cooperating ears to provide the pivotal mounting for the pedal.

The novel graduating spring contemplated by the present invention is preferably formed as a plurality of spring leaves 29, 30 and 31, one end of said leaves being rigidly secured to the forward portion of the pedal 25 between portions 28 thereof as by means of a screw 32. Intermediate this last named connection and the pivotal mounting 28, the pedal 25 is provided with a bracket 33 having a rod or pin 34 against which the lower leaf spring 29 is maintained with a certain pressure as determined by the tension of spring leaves 29, 30 and 31. If desired, this tension may be varied by inserting or removing one or more shims 35 between the pedal 25 and the upper leaf spring 31. It will be readily understood from the foregoing description that the graduating spring assembly 24 is carried by and movable with the pedal 25 and has its lower end resiliently maintained in contact with the pin 34 with a certain predetermined degree of loading or tension.

Means are provided for operatively connecting the lower end of the graduating spring 24 with the tubular member 19, and, as shown, such means include a pin 36 receivable in a recess 37 provided in the member 19, the lower end 38 of the spring leaf 29 being so formed as to conform to the upper portion of the pin 36. The foregoing connection is such that movement of the pedal 25 will be efficiently imparted to the member 19 through the graduating spring 24 as the pedal moves about the pivotal mounting 28.

In order to maintain the parts in the normal position shown in Fig. 1 and with the pin 36 in contact with the graduating spring, resilient means, such as spring 39, is interposed between an abutment 40 formed on the casing section 4 and an annular shoulder 41 formed on member 19. There is also preferably provided an adjustable pedal stop 42 cooperable with a pin 43 secured to the lower end of the pedal 25, such stop being adjustable for the purpose of positioning the pedal and its associated graduating spring 24 in proper cooperative relationship with the pin 36 in member 19 irrespective of the variations in tension of the graduating spring caused by the addition or removal of the adjusting shims 35.

In utilizing the valve structure heretofore provided with a remote operation of vehicle controlling elements, the intake chamber 11 is connected with a fluid pressure reservoir 44 as by conduit 45, while the outlet chamber 7 is connected to a fluid pressure actuator 46 as by means of a conduit 47. Actuator 46 may be connected to any suitable device 48 to be actuated.

In operation, and considering the parts are so adjusted that the intake valve 14 is closed and the plunger 17 is spaced slightly about the exhaust valve 13, as shown in Fig. 1, depression of the pedal 25 will move the member 19 downwardly through the precompressed graduating

spring 24. Such downward movement of member 19 will be accompanied by movement of the diaphragm 20 and plunger 17 carried thereby, the lower end of the latter contacting the exhaust valve 13 and thus interrupting communication between the outlet chamber 7 and the exhaust chamber 8. Further movement of the pedal 25 will effect opening of intake valve 14, whereupon fluid pressure from the reservoir will be conducted directly to the outlet chamber 7 by way of conduit 45, intake chamber 11 and open intake valve 14. In order to delay the application of fluid pressure from the outlet chamber 7 to chamber 49 immediately below the diaphragm 20, a choke 50 is interposed in the partition 6. With such an arrangement, the rate of pressure build-up within the actuator 46 supplied from chamber 7 will be materially greater than the rate of pressure build-up within chamber 49 beneath the diaphragm 20, and the actuator will be promptly actuated notwithstanding the fact that it is positioned remotely as regards the controlling valve mechanism. It will also be noted that this action will be reversed when the valve is moved to exhaust position and hence the exhausting phase of the actuator will likewise take place rapidly.

It will be understood that, after the first initial movement of the pedal 25, assuming that the same remains in this position, sufficient pressure must be built up beneath the element 20 in order to overcome the precompression force existing in spring 24 before the element 20 can effect upward movement of the plunger 17 in order to permit closing of the intake valve 14. Thus, with a slight initial pressure on the pedal 25, a substantial pressure may be promptly created within the actuator 46 connected with chamber 7 before the valve mechanism laps. Preferably, the initial increment of pressure supplied by the valvular mechanism is such as to overcome the starting friction and any biasing forces residing in the actuator and the vehicle controlling elements connected thereto. In order to secure this desirable result, the graduating spring 24 is initially precompressed or tensioned by means of shims 35 to such a value that the initial operation of the valvular mechanism will yield this desirable pressure.

Following successive movements of the pedal 25 in order to secure increases in the pressure of the fluid supplied the actuator 46 by the valvular mechanism, should it be desired to convey full reservoir pressure to the actuator, it is only necessary to depress the pedal 25 to such a position that a boss 51 carried by the pedal engages the end 38 of the leaf spring 29. It will be readily understood that further movement of the pedal 25 after such contact takes place will positively move the member 19 and parts carried thereby downwardly, as viewed in Fig. 1, in order to positively maintain the intake valve 14 in open position.

In order to prevent leakage of exhaust air into the driver's compartment, a sealing washer 52 is interposed between member 19 and an upstanding flange 53 formed on the top of casing section 4, such construction also preventing dirt and dust from entering the valve mechanism.

There is thus provided by the present invention a novel self-lapping valvular mechanism for controlling the flow of pressure fluid. The use of a graduating spring of the leaf-spring type enables a unitary and compact assembly to be achieved and one which may be readily and efficiently mounted upon the actuating pedal for the

valve mechanism. It is, moreover, to be pointed out that, in utilizing a graduating spring of this type, a certain amount of friction exists between the leaves of the spring and this serves to efficiently avoid any tendency of the valve parts to vibrate or chatter. The combined pedal and spring construction also facilitates assembly of the parts as well as rendering them more accessible for inspection and repair.

While one embodiment of the invention has been disclosed herein and has been described with considerable particularity, it is to be understood that the invention is not limited to the form shown but is capable of a variety of mechanical expressions. It will be further understood that various rearrangements of the parts may be resorted to and certain elements used without others without departing from the spirit of the invention, as is well understood by those skilled in the art. Reference will, therefore, be had to the appended claims for a definition of the limits of the invention.

What is claimed is:

1. Fluid pressure control valve mechanism comprising a casing, a partition therein formed with an intake valve seat, said partition dividing the casing into intake and outlet chambers, a spherical exhaust valve in the outlet chamber, a spherical intake valve in the intake chamber, means rigidly interconnecting said valves, a spring interposed between said exhaust valve and partition for supporting said valves, a valve-actuating member formed with an exhaust passage, a pressure-responsive element carried by said valve-actuating member and adapted to be subjected to the pressure of the fluid in the outlet chamber, and means for actuating said last member comprising a pedal pivotally mounted on said casing together with a graduating spring mounted on and carried by the pedal and having a part thereof operatively connected with said member.

2. A control valve for fluid pressure mechanism comprising a casing, a pressure-responsive member forming a pressure chamber in said casing, inlet and exhaust valves in said casing for controlling the flow of pressure fluid into and out of said chamber, means for operatively connecting said valves and member, a precompressed leaf graduating spring associated with said member, and a pivotally-mounted manually-operable device carrying said spring and having a portion thereof rigidly mounted thereon and movable to operate said member through said spring.

3. In combination with a fluid motor, means including a remotely-positioned self-lapping valvular mechanism for controlling the flow of fluid to and from the motor, said mechanism including exhaust and intake valves, an actuating assembly for said valves including a pressure-responsive member, a manually-operable element, and a precompressed leaf graduating spring having a portion rigidly attached to said element and carried by and movable with said element, said spring being operatively connected with said pressure-responsive member.

4. A control valve for fluid pressure mechanism comprising a casing, a pressure-responsive member forming a pressure chamber in said casing, inlet and exhaust valves in said casing for controlling the flow of pressure fluid into and out of said chamber, means for operatively connecting said valves and member, a manually-operable pedal pivotally mounted on said casing, and a precompressed leaf spring carried by said pedal

10 and having one end thereof rigidly connected with said pedal and having the other end operatively connected with said member.

5. A self-lapping control valve for fluid pressure mechanism comprising a casing, a diaphragm in said casing dividing the same into outlet and exhaust chambers, inlet and exhaust valves in said casing for controlling the flow of pressure fluid into the outlet chamber and from the outlet chamber into the exhaust chamber, means within the casing for operating said valves upon movement of said diaphragm, and means for moving the diaphragm comprising a manually-operable member having a leaf spring rigidly carried thereby, one end of said leaf spring being operatively connected with the diaphragm whereby movement of the manually-operable member will cause movement of the diaphragm through said leaf spring.

15 6. A control valve for fluid pressure mechanism comprising a casing, a pressure-responsive member forming a pressure chamber in said casing, inlet and exhaust valves in said casing for controlling the flow of pressure fluid into and out of said chamber, means for operatively connecting said valves and member, means for moving said member to operate said valves, said last named means including a pedal mounted on said casing, a leaf spring having one end thereof rigidly connected to and movable with the pedal, and means connecting the other end of said spring with said member.

20 7. A control valve for fluid pressure mechanism comprising a casing, a diaphragm forming a pressure chamber in said casing, inlet and exhaust valves in said casing for controlling the flow of pressure fluid into and out of said chamber, means for operatively connecting said valves and member, means for moving said member to operate said valves, said last named means including a pedal mounted on said casing, a leaf spring having one end thereof rigidly secured to said pedal, a diaphragm-actuating element carried by the diaphragm, and means operatively connecting the other end of said spring with said element.

25 8. A self-lapping control valve for fluid pressure mechanism comprising a casing having inlet and exhaust valves mounted therein, means for operating said valves including a pedal pivotally mounted on the casing and having a supporting member connected thereto, a leaf spring having one end rigidly secured to the pedal, means associated with said spring for resiliently maintaining the other end of the spring in engagement with said supporting member, and means for operatively connecting said other end with said valves.

30 9. A self-lapping control valve for fluid pressure mechanism comprising a casing having inlet and exhaust valves mounted therein, means for operating said valves including a pedal pivotally mounted on the casing and having a supporting member connected thereto, an element having one end connected to the pedal, a leaf spring having one end connected to the pedal and bearing against said element for maintaining the other end of said element in engagement with said supporting member with a predetermined degree of pressure, and means operatively connecting said other end with said valves.

35 10. A self-lapping control valve for fluid pressure mechanism comprising a casing having inlet and exhaust valves therein, means for operating said valves including a pivotally-mounted pedal,

resilient means carried by said pedal, means including a pressure-responsive member for connecting said resilient means and valves for actuating the latter upon movement of said pedal, and means for adjusting the normal position of 5 the pedal.

11. A control valve for fluid pressure mechanism comprising a casing, a pressure-responsive member forming a pressure chamber in said casing, inlet and exhaust valves in said casing for controlling the flow of pressure fluid into and out of said chamber, means for operatively connecting said valves and member, means for moving said member to operate said valves, said last named means including a pedal mounted on said 15 casing, a leaf spring having one end thereof se-

cured to said pedal, a diaphragm-actuating element carried by the diaphragm, sealing means interposed between said casing and element, and means operatively connecting the other end of said spring with said element.

12. The combination with a fluid pressure control valve mechanism having a casing, inlet and exhaust valves, and a member for actuating said valves, of means for operating said member including a pedal pivotally mounted in relation to said casing and a resilient member carried by and solely positioned by said pedal in operative relationship with said member for actuating said valves in response to movement of said pedal.
